(57) CLAIM

The ornamental design for a diaper changing pad cover, as shown and described.

DESCRIPTION

FIG. 1 is a top elevation view of the diaper changing pad cover with a strap in an unfastened position;

FIG. 2 is a front elevation view;

FIG. 3 is side elevation view;

FIG. 4 is an enlarged detail top elevation view with the strap in a fastened position; and

FIG. 5 is an enlarged detail rear (underside) elevation view;
and,

FIG. 6 is a top elevation of the diaper changing pad cover in-use.

The broken lines represent an infant that show an exemplary environment of use and form no part of the claim.
